US00D591700S

(12) **United States Design Patent**
Vojtila et al.

(10) **Patent No.:** **US D591,700 S**
(45) **Date of Patent:** **** May 5, 2009**

(54) **INSULATION BARRIER FOR ELECTRICAL POWER EQUIPMENT**

(75) Inventors: **Robert Vojtila**, Southington, CT (US);
Mark Hatje, Cheshire, CT (US);
Herbert Kleinegger, Bristol, CT (US)

(73) Assignee: **Midsun Group, Inc.**, Southington, CT (US)

CLAIM

The ornamental design for an insulation barrier for electrical power equipment, as shown and described.

DESCRIPTION

FIG. 1 is a perspective view of an insulation barrier for electrical power equipment showing our new design;

FIG. 2 is a top plan view thereof; a bottom plan view being a mirror image thereof;

FIG. 3 is a right-side elevational view thereof; a left-side elevational view being a mirror image thereof;

FIG. 4 is a front elevational view thereof; and,

FIG. 5 is a rear elevational view thereof.
